UNITED STATES PATENT OFFICE.

ALBERT BALL, OF CLAREMONT, NEW HAMPSHIRE, ASSIGNOR TO THE SULLIVAN MACHINERY COMPANY, OF SAME PLACE.

DEVICE FOR HOLDING PACKING.

SPECIFICATION forming part of Letters Patent No. 623,127, dated April 18, 1899.

Application filed May 20, 1898. Serial No. 681,198. (No model.)

To all whom it may concern:

Be it known that I, ALBERT BALL, a resident of Claremont, in the county of Sullivan and State of New Hampshire, have invented 5 a new and useful Improvement in Devices for Holding Packings; and I do hereby declare the following to be a full, clear, and exact description thereof.

My invention relates to a device for holding and fastening packing.

For the purpose of packing piston-valves and pistons for driving-valves located in the air-chests of coal-cutting, rock, and like machines where air is used the common practice has been to use metal rings to prevent 15 leakage, such as are used for ordinary pistons operated in cylinders. The diameter of these pistons is usually so small that metal rings do not work as well as on pistons of 20 larger diameter, so that many of such pistons are used without any means for preventing leakage, and when they get worn so as to leak badly new ones have to be substituted. When metal rings are used, the rings can be 25 renewed, but they are very troublesome to put in place; but where leather or like flexible material is employed the trouble is obviated, as the leather can be used a long time without leakage and when worn out can easily 30 be replaced by new ones.

The object of my invention is to provide a simple and effective device for holding leather or like flexible packing securely in place and one which can be quickly adjusted for the 35 purpose of securing the packing or releasing the same when worn out.

To these ends my invention comprises the novel features hereinafter set forth and claimed.

40 To enable others skilled in the art to make and use my invention, I will describe the same more fully, referring to the accompanying drawings, in which—

Figure 1 is a longitudinal section of a suitable air-chest with a piston-valve therein and showing my invention applied thereto. Fig. 45 2 is an enlarged sectional view of the device for holding and fastening the packing removed. Fig. 3 is a plan view. Fig. 4 is a 50 modified form of my invention.

Like letters indicate like parts in each of the figures.

While I will describe my invention as applied to the packing of a valve-piston such as is employed in the air-chest of a coal-cutting machine, yet I do not wish to limit my invention in any way to this particular application of it, but desire to include within its scope all the uses to which it may be found applicable.

60 The letter *a* represents a suitable air or steam chest having the inlet *a'* and the cylindrical chambers *b b'*. Within said chambers *b b'* and adapted to reciprocate therein are the pistons *c c'*, respectively, which are 65 connected by the connecting-piece *c²*. These pistons *c c'* and connecting-piece *c²* form an ordinary piston-valve such as employed in coal-cutting machines for moving the valve which controls the ports to the main cylinder. Within the air-chest and surrounding the chambers *b b'* are the annular shoulders or bearing-faces *d d'*, respectively. These bearing-faces form seats for the leather or like flexible packing *e*. Pressing against the 70 packing *e* and adapted to hold said packing tightly against the bearing-faces *d d'* are the holders *f f'*. The holders *f f'* are held against the packing by means of the rods or bolts *g*, the ends *g'* of said rods fitting in seats *h*, 75 formed for them in the holder *f*. Two of these rods *g* are shown, although it is apparent that the number may be increased, if desired. The opposite ends of said rods *g* are threaded and engage with the threaded seats 80 *i*, formed in the holder *f*. Check-nuts *k* engage the threaded portion of said rods and are adapted to lock said rods in position when once they have been properly adjusted. The rods are provided with the enlargements *l*, 85 90 by means of which they may be readily turned.

95 From the above construction it is readily apparent that when it is desired to force the holders *f f'* against the packing *e* it is only necessary to turn the rods *g* until the proper impression of the packing has been reached, whereupon the nuts *k* are screwed up to hold the rods in this position. The holders force the packing into close contact with the bear- 100

ing-faces d d' and form a very tight joint, so that all leakage is practically precluded. When the packing wears out, it is a very simple operation to release the rods g and re-
5 move the packing and substitute new packing therefor.

In the form above illustrated the pistons c c' are of different diameters; but it is apparent that both pistons can be of the same
10 size without affecting the invention. By having the rods g threaded into the holder f the holder cannot fall therefrom when handled.

In Fig. 4 I have illustrated another form
15 of my invention, in which the rods m m' both fit within threaded seats n in the holders, the inner ends of said rods being adapted to abut against the rigid projection o on the air-chest. In the same manner as above described the
20 holders may be forced against the packing by turning the rods m m' ; but in this case each holder is operated independently and one can be released without the other.

What I claim as my invention, and desire to secure by Letters Patent, is—

25 1. The combination with a suitable shell or casing having a cylindrical chamber therein and an annular bearing-face surrounding the same, of a packing of flexible material, a holder adapted to hold said packing against
30 said bearing-face, a rod extending out from

said holder, a stop for said rod, and means for forcing said holder against said packing, substantially as set forth.

2. The combination with a suitable shell or casing having opposite cylindrical chambers 35 with annular bearing-faces surrounding the same, of a packing of flexible material, holders adapted to hold said packing against said bearing-faces, rods extending from one holder to the other and means for forcing said holders against said packing, substantially as set forth.

3. The combination with a suitable shell or casing having opposite cylindrical chambers with annular bearing-faces surrounding the 45 same, of a packing of flexible material, holders adapted to hold said packing against said bearing-faces, rods extending from one holder to the other, one of said holders having seats therein for the reception of said rods and the 50 other holder having threaded seats therein for the reception of the opposite ends of said rods, substantially as set forth.

In testimony whereof I, the said ALBERT BALL, have hereunto set my hand.

ALBERT BALL.
